UNITED STATES PATENT OFFICE.

CHARLES W. LOGAN, OF KENMORE, NEW YORK, ASSIGNOR TO MARKEL ELECTRIC PRODUCTS, INC., OF BUFFALO, NEW YORK, A CORPORATION OF NEW YORK.

DESIGN FOR A SPIDER FOR CHANDELIERS.

Application filed November 23, 1928. Serial No. 29,020. Term of patent 3½ years.

To all whom it may concern:

Be it known that I, CHARLES W. LOGAN, a citizen of the United States, residing at Kenmore, in the county of Erie and State of New York, have invented a new, original, and ornamental Design for a Spider for Chandeliers, of which the following is a specification, reference being had to the accompanying drawing, forming part thereof.

In said drawing:

Figure 1 is a bottom plan view of a spider for chandeliers embodying my new design.

In this form the applied ornamentation is shown in full lines on one of the arms of the spider, and the outline of the spider is completed by dot and dash lines, it being understood that the applied ornamentation is repeated throughout the area of the spider.

Figure 2 is a side elevation partly in full lines and partly in dot and dash lines.

I claim:

The ornamental design for a spider for chandeliers, substantially as shown.

CHARLES W. LOGAN.
